CAR DOOR STRUCTURE

Axel Wasberg, Chicago, Ill., assignor to Chicago Railway Equipment Company, Chicago, Ill., a corporation of Illinois

Application March 5, 1934, Serial No. 713,970

23 Claims. (Cl. 20—22)

This invention relates to sliding doors, particularly for railway house cars, and consists in novel means for applying frictional resistance to movement of the door to prevent slamming thereof against the door posts.

Car doors mounted on roller or ball bearings have been heretofore in use and in order to prevent destructive slamming of the door in case of sudden shocks, means have been provided for lowering the door relative to the bearings to render the same inoperative and apply frictional resistance to sliding of the door. The vertical movement of the door has been generally effected by providing recesses in the stationary doorway track into which the anti-friction bearings may drop, or by some form of eccentric mounting of the bearing. In either case, a portion of the door frictionally engages the doorway track when the door is lowered and means is provided for elevating the door to permit normal functioning of the bearings. Such devices have frequently been of rather complicated and expensive construction, subject to operating difficulties due to wear of parts, and ineffective under certain conditions.

An object of the present invention is to provide novel means for raising and lowering a sliding door relative to its bearings, which means is lowered when the door is at rest and which may be conveniently and easily raised to permit normal functioning of the door bearings when the door handle is moved in either door opening or door closing direction.

Another object is to provide novel means for frictionally resisting sliding of the door which automatically become operative when the door approaches either the full open or closed position to prevent slamming of the door.

Another object is to provide a device of the above type which is sturdy, durable and economic of construction, simple in operation and maintenance, and effective under the most exacting conditions.

These objects and others hereafter appearing are attained by the structures illustrated in the accompanying drawings, in which—

Figure 1 is a side view of a part of a car door illustrating one form of the invention.

Figure 2 is a similar view of the same, showing the parts in a different position.

Figure 3 is a fragmentary vertical longitudinal section through the door and doorway bearing tracks and showing the door partially open.

Figure 4 is a horizontal section taken approximately on the line 4—4 of Figure 1.

Figures 5, 6, and 7 are detail vertical trans-

verse sections taken on the corresponding section lines of Figure 1.

Figures 8 and 8a are detail side views showing one of the door elevating bell cranks in different positions, the bearing tracks being sectioned. 5

Figures 9 and 9a are similar views showing another of the bell cranks.

Figures 10 is a view corresponding to Figures 8 and 9 but showing modified mechanism.

Figures 11 and 12 are views corresponding to Figures 1 and 2 and showing another modification.

Figures 13 and 14 are detail vertical transverse sections taken on the corresponding section lines of Figure 11. 15

Figure 15 is a detail horizontal section taken on the line 15—15 of Figure 11.

Figures 16 and 17 are views corresponding to Figures 11 and 12 but showing still another modification.

Figure 18 is a detail vertical transverse section taken on line 18—18 of Figure 16. 20

Figure 19 is a detail horizontal section taken on line 19—19 of Figure 16.

Figure 20 is a side view showing a detail of the 25 structure in Figure 16, portions being broken away and sectioned.

In Figures 1 to 9a, inclusive, is shown a box car sliding door formed of metal panels 1, front and rear edge framing members 2 and 3 of Z-30 section, member 3 being slightly deformed, bottom edge members 4 and 5 forming a downwardly opening bearing track or housing, and a top edge frame (not shown). Any suitable type of door may be provided and the front and rear 35 edge members 2 and 3 are suitably shaped to cooperate with the door posts 6 and 7 to form weather and spark seals. The door and weather seal means do not in themselves constitute the present invention. The door is carried by means 40 of the anti-friction balls 8 upon what may be termed the stationary or doorway track 9 secured by brackets 10 to the car side sill 11 beneath the flooring 12.

In order to prevent too free movement of the 45 door as it approaches its full open and full closed positions, the door track member 4 is slotted or recessed as at 13, and the balls 8 are positioned relative thereto so as to enter the slots when the door is positioned a short distance from said full open and full closed positions. When the balls enter slots 13, the door will drop sufficiently to cause the lower extremity of the door edge members 2 and 3 to rest on track 9, rendering the anti-friction bearings inoperative and applying con- 55

siderable frictional resistance or drag to further movements of the door in either direction. The slots and balls may be positioned, satisfactorily, so as to drop the door at points approximately eighteen inches from the full open and full closed positions, so that in case the door is left partially open or is not securely fastened, there will be sufficient drag to prevent the door slamming against the door post in case of a sudden jolt.

10 Pivoted to brackets 14a, 15a, 16a, and 17a on the upper vertical flange 4a of the door track member 4 adjacent slots 13 are the bell cranks 14, 15, 16, and 17 for elevating the door, after the balls 8 are received in slots 13, to again 15 render the anti-friction bearings operative. The cranks have arms 18, 19, 20, and 21 pinned between the flanges of a bar 22 of inverted U-section extending above the door track and movable longitudinally to rotate all the bell cranks 20 in unison. Secured to the center of bar 22 is a bracket 23 having vertically spaced lobes 24. Pivoted to an extension 23a on bracket 16a is a handle lever 25 having lugs 26 disposed to engage lobes 24 to impel bar 22 longitudinally 25 in the same direction, that is, to the right, when the lever is swung either towards the front or rear edges of the door.

The bell cranks 14 and 16 and 15 and 17 are identical, these being shown in detail in Figures 30 8 and 8a and Figures 9 and 9a, respectively. With reference to Figures 8 and 8a, the crank 16 includes, besides the arm 20, a toe 27 and a heel 28. Toe 27 is disposed to bear against the ball 8 when received in slot 13 and when the 35 crank is rotated clockwise from the rest position shown in Figure 8, the door will be raised by leverage and the bottom surface 29 of the toe moved flush with the bearing surface of track member 4, as shown in Figure 8a. The flush position of the toe is assured by engagement of fins 30 with track 4 at the edges of slot 13. The heel 28 serves as a stop for the ball 8 to provide an initial drag and to stop the ball immediately beneath recess 13 while the door is elevated and before ball 8 has been permitted to enter the recess. Heel 28 is shown as clearing the doorway track 9 in the rest position in Figure 8, but this member may be of sufficient length to rest on the track in this position to provide 50 additional frictional resistance and assist in supporting the door.

The bell crank 15 (Figures 9 and 9a) includes the arm 19 and a toe portion 31 having a flat surface 32 engaging ball 8 disposed flush with track member 4 and forming a continuation thereof, as in Figure 9a, when the door is raised. Fins 33 correspond with fins 30 in Figure 8. Depending from the extremity of the toe is a finger 34 serving as a ball stop similarly to the heel 28 60 in Figure 8.

The lever 25 provides a convenient handle to be grasped in sliding the door. When the lever is disposed vertically, as in Figure 1, the bell crank toes will be lifted, as in Figures 8 and 9, 65 permitting the balls 8 to be received in recesses 13 and thereby rendered inoperative. When the lever is moved in either the door opening or door closing directions, as indicated in Figure 2, the door will be raised, permitting free sliding thereof in one direction on the anti-friction bearings. During sliding of the door by an operator, the balls will be stopped eighteen inches before the full open or full closed position is reached, but the drag will not be excessive so 70 long as force is applied to the lever. When the

lever is released, the door edge members 2 and 3 drop automatically onto the track 9, materially increasing the frictional resistance in either direction. Obviously, therefore, the door is not free to slam against the door posts under any 5 conditions, but upon application of force to the handle lever, may be easily moved as desired.

In Figure 10, the anti-friction balls 35 are provided with a cage 36 to insure proper spacing thereof. The bell cranks 37 correspond in general with the cranks 20 in Figure 8 except that no depending ball stop is provided. The remainder of the mechanism may be identical to that in the form just described. With this arrangement the door may be freely moved on its 15 bearings so long as the handle lever (not shown) is maintained at either side of the rest position. When the lever is upright, the slots 38 will be free to receive the balls. This construction has the advantage that no frictional resistance is 20 offered to intentional movement of the door by an operator, but in case the door is left partially open or not securely locked when closed, the bearings automatically will be rendered inoperative before the door can slam either open or 25 closed in case of a sudden jolt. The bearing cage itself does not affect the operation of the device, and may be omitted. If desired, the cage may be of sufficient thickness to support the door in its lowered position and provide additional friction surface.

In Figures 11 to 15, the slots 39 in the door track member 49 are at one side thereof and are not of sufficient width to receive the balls 41 and drop the door. Each of the bell cranks 42 pivoted to the door track has a depending finger stop 43, insertable through the adjacent slot 39 to obstruct the ball passage, and an arm pinned to the bar 44 operated by handle lever 45, as in Figures 1 to 10. Fins 46 limit the 40 counter-clockwise movement of the cranks.

In order to provide additional frictional resistance, a brake 47 is carried by the door adjacent doorway track 48 by means of links 49 and 50 pivoted to a bracket 51. Link 50 includes an 45 upwardly projecting finger 52 forming a bell crank therewith and disposed to be engaged by bracket 53 on bar 44 to lift the brake. Since the position of bracket 53 is controlled by handle lever 45, it is obvious that when the lever is upright, as in Figure 11, the member 47 will be dropped into engagement with the track 48 whereupon the brake will operate by toggle action to frictionally resist movement of the door in the closing direction. With the use of this 55 type of brake, means (not shown) must be provided for preventing vertical movement of the door which would nullify the toggle effect. Preferably the ball stop cranks and brake will be operated simultaneously by a single movement 60 of the handle lever, as shown, although the bell cranks and brake may be operated separately.

In Figures 16 to 20, the door 54 is mounted upon the stationary track 55 by means of roller bearings 56 having spindles 57 journaled in the 65 sides of hollow approximately semi-cylindrical carriages 58. Secured to the lower edge of the door are hollow retainer housings 59 having downwardly opening slots 60 in their side walls receiving the eccentric trunnions 61 rigid with and projecting laterally from carriages 58. Projecting upwardly from carriages 58 are bifurcated arms 62 pinned to horizontal bar 63 which is longitudinally reciprocated by handle lever 64. Pins 61 and slots 60 are offset from the roller spindles 70 75

57 and constitute eccentric mountings of the door on the rollers whereby reciprocation of bar 63 will raise and lower the door. Each roller and its carriages may be assembled as a unit with the 5 bearing retainer 59 after it is permanently mounted on the door. When the lever is upright, as in Figure 16, the door will be supported frictionally upon track 55 and the roller bearings will be inoperative. Movement of the lever in 10 either direction from the center position, as indicated in Figure 17, will apply the weight of the door to the anti-friction bearings.

The mechanism above described is of rugged construction and is simple, convenient, and easy 15 to operate. When the handle lever is at rest, sufficient resistance is offered to the sliding of the door as it approaches the full open and closed positions to prevent slamming thereof in either direction even in case of a heavy jolt, but manipulation of the lever in either direction avoids or 20 materially lessens this resistance to facilitate intentional movement of the door. Moreover, in each form except Figures 11 to 15, the door lowering mechanism will function automatically to 25 prevent destructive slamming and when the door is lowered resistance is applied to movement thereof in either direction.

The novel door elevating mechanism may be varied in details as will occur to those skilled in 30 the art and the exclusive use of all such modifications as come within the scope of the appended claims is contemplated.

I claim:

1. In combination, a sliding door, a track 35 adapted to frictionally support said door in its lowered position, spaced anti-friction bearings adapted to support said door on said track in the raised position of said door, a member movable longitudinally in one direction only to elevate 40 said door and render all of said bearings operative and movable in the opposite direction only to lower said door and render all of said bearings inoperative, and a lever pivoted to said door and swingable in door opening and door closing directions, said door being lowered in one position of 45 said lever and said lever operating when swung in either direction from said position to move said member in the door elevating direction.

2. In combination, a sliding door, a track 50 adapted to frictionally support said door in its lowered position, spaced anti-friction bearings adapted to support said door on said track in the raised position of said door, and means for rendering said bearings operative and inoperative 55 comprising a continuous bar mounted on said door and movable longitudinally in opposite directions, respectively, to raise and lower said door, there being abutments on said bar spaced transversely of the length thereof and a handle lever 60 for sliding said door and swingable from a rest position in door opening and door closing directions, said lever having elements disposed to cooperate with said abutments to move said bar in the same direction in either direction of lever 65 movement from said rest position.

3. Structure as defined in claim 2 in which said lever is located between said bearing elements and vertically disposed when said door is lowered.

4. In combination, a doorway, a sliding door 70 having a bearing track, an anti-friction bearing for supporting said door track in said doorway, there being a recess in said door track for receiving said bearing to render the same inoperative, and mechanism mounted on said door for manual operation for elevating said door inde-

pendently of the sliding movement thereof to render said bearing operative.

5. In combination, a doorway and a sliding door 5 having bearing tracks, anti-friction bearings between said tracks, there being recesses in said door track for receiving said bearings to render the same inoperative, sliding of said door being frictionally resisted when said bearings are in said recesses, and a member on said door to be grasped by the hand of an operator to open said door and mechanism operated automatically by door opening movement of said member for elevating said door track independently of the sliding movement of said door to avoid said resistance and render said bearings operative. 15

6. In combination, a doorway, a sliding door having a bearing track, an anti-friction bearing for supporting said door track in said doorway in the raised position of said door, and a recess in 20 said track for receiving said bearing to render the same inoperative, said bearing and said recess being disposed to interengage when said door is spaced from its extremity of movement in one direction to apply a drag to further movement 25 of the door in said direction and means for relieving the door of drag during initial movement of the door in the opposite direction.

7. Structure as specified in claim 6 in which recesses are provided in said door track for respectively receiving said bearing as the door 30 approaches its full open and its full closed positions to apply a brake to movement of said door to either of said positions.

8. In combination, a doorway and a sliding door 35 having bearing tracks, an anti-friction bearing for supporting said door track on said doorway track in the raised position of said door, a recess in said door track spaced from the front and rear edges of said door for receiving said bearing to lower said door and apply a drag to movement thereof in one direction, and door raising mechanism including an element depending from said track adjacent said recess for stopping movement 40 of said door in said direction relative to said bearing, said element resting on said doorway track when said door is lowered to relieve said bearing 45 of the weight of said door.

9. In combination, a doorway, a sliding door 50 having a bearing track, an anti-friction bearing for supporting said door track in said doorway in the raised position of said door, a recess in said door track for receiving said bearing to lower said door and apply resistance to movement thereof in one direction, and a member on said door adjacent said recess and adapted to be moved to engage said bearing when in said recess and raise said door, said member having a surface flush with said door track and forming part thereof when said door is raised. 55

10. In combination, a doorway, a sliding door having a bearing track, an anti-friction bearing for supporting said door track in said doorway in the raised position of said door, a recess in said door track for receiving said bearing to lower said 60 door and apply resistance to movement thereof, and a member pivoted on said door adjacent said recess and including a stop element for engaging said bearing to limit relative movement of the same and said door, structure for raising said door 65 when said member is rotated, and a surface disposed to lie flush with said door track in said recess to prevent the entrance of said bearing into said recess when said door is raised. 70

11. In combination, a doorway, a sliding door 75

- having a bearing track, an anti-friction bearing for supporting said door track in said doorway when said door is in its raised position, a recess in said track for receiving said bearing to lower 5 said door and apply resistance to movement thereof, a bell crank having an arm arranged when rotated in one direction to raise said door, and a handle lever facilitating sliding movement of said door and operatively associated with the 10 other arm of said bell crank, said bell crank being rotated in the door raising direction to render said bearing operative when said lever is rotated in either the door opening or the door closing direction.
- 15 12. Structure as specified in claim 11 in which a plurality of said bearings, recesses, and the associated bell cranks are provided and all of said bell cranks are operated by said lever.
- 20 13. Structure as specified in claim 11 in which the first-mentioned arm of said bell crank includes a surface disposed to lie flush with said door track in said recess when said door is raised to render said bearing operative.
- 25 14. In combination, a doorway and a sliding door having bearing tracks, an anti-friction bearing supporting said door track on said doorway track, and a stop member movably mounted on said door in position to obstruct the movement of said bearing along one of said tracks and resist the sliding of said door, and manually operative mechanism for moving said stop member from said obstructing position to permit free sliding of said door on said bearing.
- 30 15. Structure as specified in claim 14 in which said mechanism automatically positions said bearing and said stop member to apply a drag to sliding of the door at a point spaced substantially from an extreme of movement thereof to prevent slamming.
- 35 16. In combination, doorway and sliding door members having bearing tracks, an anti-friction bearing between said tracks, means for resisting sliding of said door including a stop element on one of said tracks for obstructing relative movement of the same and said bearing and a device on one of said members for frictionally engaging the other, and a handle movably mounted on said door and associated with said stop element and said device so as to render the same inoperative 40 when moved in one direction.
- 45 17. Structure as specified in claim 16 in which said stop element and said device are in their operative positions when said handle is in one position, said handle facilitating sliding of the door and being movable in door opening and door closing directions from said position and rendering said stop element and said device inoperative when moved in either of said directions.
- 50 18. Means for supporting a sliding door comprising a roller, a carriage journalling said roller and having laterally projecting trunnion structure disposed eccentrically of the roller, and a retainer for mounting said roller and carriage on the door, said retainer having a bottom opening for insertion of said carriage and roller and the sides of said retainer having downwardly 55 opening slots for receiving said trunnion structure.
- 5 19. In combination, a sliding door, a bearing track therefor, a bearing retainer secured to said door and having a wall with a slot opening in an edge thereof, a carriage, a roller journalled therein, and means for rotating said carriage about said roller journal, said carriage having a trunnion located eccentrically of the roller journal and insertable in said slot for elevating said door, said carriage and roller being applicable as a unit to said retainer after the latter is mounted on said door and said trunnion and slot functioning to maintain said retainer, carriage, and roller assembled when mounted on 10 said bearing track without other holding means.
- 10 20. In combination, a sliding door, a bearing track therefor, a plurality of mechanisms on said door for raising the same on said track, each of said mechanisms including a retainer secured to 15 the door, a carriage, a roller journalled in said carriage, and a bearing on said carriage located eccentric of the roller journal for engaging said retainer, a bar engaging the carriages of each of said mechanisms and longitudinally reciprocable to rotate said carriages about said roller journal and raise and lower said door through said eccentric bearing, a handle lever pivoted to said door and swingable in door opening and door closing directions, and cooperating 20 elements on said bar and said lever functioning to move said bar longitudinally in the door elevating direction when said lever is moved in either direction.
- 25 21. In combination, sliding door and doorway 25 members, a bearing track rigid with said door member, an anti-friction bearing between said track and said doorway, and mechanism on said door including a lever pivoted to said door member and an element movable by said lever and co-operable with said anti-friction bearing to raise 30 said door to cause the same to roll freely thereon and lower said door to cause the same to frictionally engage said doorway.
- 30 22. In a support for a sliding door, a housing 35 arranged for application to the side of the door and having bottom and top openings, there being downwardly opening recesses in the sides of said housing, a roller, a carriage journalling said roller and having laterally projecting trunnions and an upwardly projecting operating arm, said carriage and roller being movable upwardly through the bottom opening in said housing to pass said arm through the top opening in said housing and to seat said trunnions against the 40 upper ends of said recesses.
- 35 23. In combination, a doorway having a bearing track, a sliding door having a bearing engaging track, an anti-friction bearing for supporting said door track on said doorway track, there 45 being a recess in said door track for receiving said bearing to lower said door onto said doorway to render said bearing inoperative, and a leverage device for elevating said door independently of sliding movement thereof to render 50 said bearing operative.

AXEL WASBERG.

DISCLAIMER

2,096,569.—*Axel Wasberg, Chicago, Ill.* CAR DOOR STRUCTURE. Patent dated October 19, 1937. Disclaimer filed August 28, 1939, by the assignee, *Chicago Railway Equipment Company*.

Hereby disclaims from the scope of claims 4, 5, 21, and 23 all devices except those in which the door operating mechanism substantially completes the elevation of the door before moving the door longitudinally of its supporting track.

[*Official Gazette September 19, 1939.*]
